DESIGN FOR A DISPLAY BOX

Lewis Douglas Young, Providence, R. I., assignor to Douglas Young, Inc., a corporation of Rhode Island

Application May 22, 1941, Serial No. 101,089

Term of patent 14 years

To all whom it may concern:

Be it known that I, Lewis Douglas Young, a citizen of the United States of America, residing at Providence, county of Providence, State of Rhode Island, have invented a new, original, and ornamental Design for a Display Box, of which the following is a specification, reference being had to the accompanying drawing, forming a part thereof.

Fig. 1 is a perspective view of the front side of one end;

Fig. 2 is a perspective view of the front side of the opposite end; and

Fig. 3 is an end elevational view of a display box, showing my new design.

The dominant feature of the design is shown in full lines.

I claim:

The ornamental design for a display box, substantially as shown and described.

LEWIS DOUGLAS YOUNG.
